UNITED STATES PATENT OFFICE.

HENRY A. OWEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

WEFT-REPLENISHING LOOM.

1,160,952.

Specification of Letters Patent.

Patented Nov. 16, 1915.

Application filed May 4, 1915. Serial No. 25,828.

To all whom it may concern:

Be it known that I, HENRY A. OWEN, a citizen of the United States, residing at Whitinsville, in the county of Worcester, State of Massachusetts, have invented a certain new and useful Improvement in Weft-Replenishing Looms, of which the following is a specification, reference being had therein to the accompanying drawings.

The invention comprises improved devices through which rocking movement of an arm in connection with the weft-detector devices of a weft-replenishing loom operates the shuttle-feeler and also moves the trans-ferrer-dog or latch, subject to the control of the shuttle-feeler, into position to be engaged by the trans-ferrer-actuating bunter. It includes, also, improved means for keeping the working end of the shuttle-feeler slightly ahead of the back wall of the shuttle-box during the forward movement of the lay at the time of the feeling action of the shuttle-feeler.

An embodiment of the invention is shown in the drawings, in which latter,

Figure 1 shows in side elevation a portion of the replenishing side of a weft-replenishing loom, with the said embodiment applied thereto. Fig. 2 is a partly sectional view showing certain of the parts of Fig. 1 looked at in the opposite direction. Fig. 3 is view, on larger scale than the preceding figures, of the slotted control arm.

Having reference to the drawings, in the illustrated embodiment of the invention the rockshaft 1, mounted in bearings at the front of the loom, and in practice combined and arranged to be rocked through the action of the weft-detector devices of the loom, has affixed thereto at the replenishing side of the loom an upstanding arm 2. The said arm is made fast to the rockshaft by means of clamping screws 2^a, 2^b, or in other approved manner, preferably with capacity for angular adjustment upon the rockshaft. It has connected thereto above the rockshaft, by means of a pivot 3, a lever 4 having a lower arm that is connected operatively with the dog or latch 5 of the trans-ferrer 6. The said lower arm constitutes the control arm for the said dog or latch. In this instance it extends rearwardly, and is formed with a slot 4^a receiving a lateral stud 5^a that projects from the dog or latch. Lever 4 has an upper arm that is connected operatively

with the shuttle-feeler 8, in this instance by means of a link 7. The shuttle-feeler is mounted by means of a pivot 9 upon the inwardly facing side of the fixed end-casting 10 of the feeler or magazine for containing the reserve supply of weft-carriers x, x, etc., loaded with weft or filling. The rear end of the link 7 is connected by a pivot 11 with an arm of the shuttle-feeler extending upward above the pivot 9 of the latter. The front end of the link is connected by a pivot 12 with the said upper arm of the lever 4, the said pivot 12 being adjustable in a horizontal slot 12^a in the said arm so as to permit adjustment of the normal position of the shuttle-feeler, and regulation of the closeness of the approach of the acting end of the feeler to the back wall of the shuttle-box.

The lever 4 is movable around pivot 3 relative to the arm 2, but normally is kept in a definite position with respect to the arm through being held against a stop at 13 upon the said arm by means of a spring 14, the latter being in this instance a contracting spiral spring having one end thereof engaged with the lower arm of lever 4 and the other end engaged with a stud 15 carried by a rearwardly-extending arm 16 fixed upon rockshaft 1. The stud 15 is adjustable in a slot 17 in the said arm 16 to enable the tension of spring 14 to be varied. Under ordinary working conditions the lever remains in contact with the stop, and when rockshaft 1 is rocked the lever 4 will move in unison with arm 2 just as though the lever was made in a single piece with the arm. The spring, however, permits the lever to move relative to the arm 2 at times, as presently will be explained.

Under ordinary conditions, therefore, when the rockshaft 1 is rocked in the direction indicated by the arrow in Fig. 1, under the control of the weft-detector devices of the loom, the arm 2 and lever 4 will move as one around the axis of the rockshaft, without any relative turning of the lever around the point 3 of its pivotal connection with arm 2. In this rocking movement the upper arm of lever 4 goes forward and through the link 7 operates the shuttle-feeler 8 so as to cause its acting portion to move rearward toward the lay. At the same time, the lower arm of the lever, in consequence of being caused to rise somewhat, raises the engaging portion of the dog or latch 5 of the trans-ferrer into the path of

the bunter 18 carried by the lay 19. This will be the action if the shuttle 20 has passed fully home into the shuttle-box at the replenishing side of the loom, between front-plate 21 and back wall 22, and consequently the bunter will engage the elevated dog or latch and the normal working in replenishment will take place. In case, however, the shuttle should not be fully entered into the said shuttle-box but should occupy an inwardly-misplaced position, partly projecting from the mouth of the shuttle-box, in which event the forward movement of the lay will carry the inwardly-projecting por-
tion of the shuttle against the acting end of the shuttle-feeler, the said end will be pressed forward by the shuttle. Under such action the spring 14 will yield to permit lever 4 to turn upon the pivot 3 connecting it with arm 2 as the shuttle-feeler is forced to swing about its pivot 9. This turning of the lever 4 around pivot 3 will carry the lower arm of the lever downward, and in going down the said lower arm will swing down the dog or latch 5 so as to depress the engaging end of the latter below the engaging end of bunter 18, thereby preventing engagement of the bunter with the dog or latch to actuate the transerrer as the lay goes forward.

In practice, the rockshaft 1 will be combined operatively with any approved weft-detector devices so as to be rocked under the control of the latter. Such devices may comprise either ordinary weft-fork mechanism arranged to rock the rockshaft upon detection of failure of weft or filling, or may comprise mechanism contrived to cause the rockshaft to be rocked when the supply of weft or filling in the shuttle in use in the loom has become depleted to the predetermined extent.

When the bunter 18 engages with the dog or latch it drives the latter forward and causes the transerrer 6 to rock around its supporting stud 6^a and transfer the leading weft-carrier to the shuttle. As one feature of the invention, I construct the inter-engaging elements of the dog or latch and the control arm therefor so that as the dog or latch is driven forward by the push of the bunter the lever 4 shall be turned upon its pivot 3 to thereby operate the shuttle-feeler 8 so as to cause the working end of the latter, at that time occupying the rearward position to which it was moved by the rocking of the breast-beam rockshaft, to move forward gradually as the lay advances, keeping thereby the acting end of the shuttle-feeler clear of the front surface of the back plate 22 of the shuttle-box, or relieving the pressure against the said surface. In the present embodiment of this feature of the invention, the slotted portion of the control arm of the lever 4 is formed with

a cam 4*. In the position of the parts represented in Fig. 1 the lateral projection or stud 5^a of the dog or latch is located in a portion of slot 4^a at the front of the said cam. When the breast-beam rockshaft 1 is rocked in the direction indicated by the arrow near it, the upward movement of the slotted control arm causes the lower wall of the slot, by its pressure against the lateral projection or stud 5^a to tilt the dog or latch upward. The tilting of the dog or latch upward carries the lateral projection or stud 5^a into a portion of the slot at the rear of the cam 4*. When now the bunter engages with the engaging end of the dog or latch and drives the dog or latch forward, the forward movement of the lateral stud or projection 5^a causes the latter to act upon the cam 4* and operate to depress the control arm, thus rocking the lever 4 around its pivot 3 and through such rocking of the lever transmitting the required movement to the shuttle-feeler to cause its acting end to travel forward in unison with the advance of the lay. To further facilitate the forward receding movement of the shuttle-feeler, I may construct and time the weft-hammer cam and weft-hammer to permit the latter to drop off the cam so as to allow the breast-beam rockshaft to recover its normal position sufficiently early in the advance of the lay.

To enable the controller-arm and its cam 4* to be adjusted into proper working relations with the stud 5^a of the transerrer-dog or latch, the stop 13 is constituted by an adjustable stop-screw, the tip of which is presented to the back of lever 4.

Arm 16 is shown as having connected to it by means of a pivot 30 a link 31 which hooks under the bearing 32 for the front end of the rotating take-up shaft 33, so that when the rockshaft 1 is rocked by the action of the weft-detector devices the said bearing and take-up shaft will be lifted to disengage the driving worm 34 of such shaft out of engagement with the worm-gear 35 of the take-up mechanism. Thereby, the taking-up action is suspended and provision is made for letting-back the cloth to prevent the formation of a thin place in the cloth. This connection of the rockshaft 1 with the take-up mechanism is utilized only in case the said rockshaft is arranged to be rocked upon failure of weft or filling. It is not needed when the said rockshaft is arranged to be rocked for such purpose by means of a feeler mechanism prior to complete exhaustion of the working supply of weft or filling.

I claim as my invention:

1. In a weft-replenishing loom, the combination with an arm adapted to be rocked through the action of weft-detector devices employed in such loom, a shuttle-feeler,

and a transerrer-dog or latch, of a lever pivotally carried by the said arm, separately connected with the shuttle-feeler and transerrer-dog or latch and controlling such elements, yieldingly held to move in definite relation with the said arm, and giving way to the encounter between a misplaced shuttle and the shuttle-feeler.

2. In a weft-replenishing loom, in combination, a shuttle-feeler, a transerrer dog or latch, a rockshaft adapted to be rocked through the action of weft detector devices employed in the loom, an arm on said rockshaft, and a give-away member carried by the said arm and through which the arm actuates the shuttle-feeler and positions the dog or latch, and through which also the shuttle-feeler controls the dog or latch.

3. In a weft-replenishing loom, the combination with an arm adapted to be rocked through the action of weft-detector devices employed in such loom, a shuttle-feeler, and a transerrer-dog or latch, of a lever movably carried by the said arm and yieldingly held in definite relation therewith, having one arm thereof operatively connected with the shuttle-feeler to actuate the latter, the said lever itself controlled by the shuttle-feeler and having another arm operatively connected with the transerrer-dog or latch to control the latter.

4. In a weft-replenishing loom, the combination with an arm adapted to be rocked

through the action of weft-detector devices employed in such loom, a shuttle-feeler, and a transerrer-dog or latch, of a lever movably carried by the said arm and held yieldingly in definite relation therewith, having one arm operatively connected with the shuttle-feeler to actuate the latter, the said lever itself controlled by the shuttle-feeler and having another arm operatively connected with the transerrer-dog or latch to control the latter, the latter arm provided with a cam through which the said dog or latch acts to swing the lever and move the feeler to carry its working end forward gradually as the lay advances.

5. In a weft-replenishing loom, the combination with an arm adapted to be rocked through the action of weft-detector devices employed in such loom, a shuttle-feeler, and a transerrer-dog or latch having a stud, of a lever movably carried by the said arm and held yieldingly in definite relation therewith, having one arm operatively connected with the shuttle-feeler to actuate the latter, the said lever itself controlled by the shuttle-feeler and having an arm slotted to receive the said stud to control the transerrer-dog or latch and provided with a cam through which the dog or latch acts to swing the lever and move the feeler to carry its working end forward gradually as the lay advances.

HENRY A. OWEN.
